UNITED STATES PATENT OFFICE.

GEORGE SCHONEMAYER, OF CLEVELAND, OHIO.

INVENTOR'S NAME.

1,184,284.

Specification of Letters Patent.

Patented Apr. 6, 1915.

Application filed November 3, 1914. Serial No. 303,360.

To all whom it may concern:

Be it known that I, GEORGE SCHONEMAYER, citizen of the United States, residing at Cleveland, in the county of Cuyahoga and State of Ohio, have invented certain new and useful improvements in Flushing-Tanks, of which the following is a specification.

This invention relates to flushing tanks for water closets and the like, and has for its object to provide an improved tank wherein different stages of water may be maintained, making it possible to use different quantities of water in flushing the closet, which is advantageous under certain conditions, as where the supply of water is not plentiful.

A further object of the invention is to improve flushing tanks in various particulars as more fully explained hereinafter.

In the accompanying drawings:—Figure 1 is a side elevation of the flushing valve apparatus, the tank being in section and portions being broken away. Fig. 2 is an opposite side elevation of the valve arrangement. Fig. 3 is a sectional view of the water inlet. Fig. 4 is a detail of the valve seat plug. Fig. 5 is a side elevation similar to Fig. 1, but showing the operating parts in a different position. Fig. 6 is an opposite side elevation of the valve arrangement, with the parts in the position shown in Fig. 5. Fig. 7 is a view in perspective of the stirrup and associated parts. Fig. 8 is a detail in perspective of a trip arm.

Referring specifically to the drawings, 4 indicates a tank or box preferably provided with a metal lining 47.

5 is the inlet pipe to the tank, provided with an upwardly projecting cylindrical member or casing 5'. A pair of arms 6 project upwardly from said member, to which is pivoted a lever 8, as indicated at 7, the pivot being slightly offset from the vertical line of the arms. The upper end of the lever 8 is slotted as indicated at 9 to receive the end of the float rod 11, which is held by a clamp 10, the float 12 being fastened to the outer end of the rod.

40 A rod 14 is connected at its upper end to the angle of the lever 8 as indicated at 13, and at its lower end to the cap 15 which has a stem 16 projecting into a hole in the upper end of the plunger 17 which fits in the bore 55 18 of the member 5'.

Secured to the lower end of the plunger 17

is a packing or gasket 19 which closes against the seat 20' of the valve seat plug 20; and these parts constitute the water inlet valve controlling the flow from the 50 inlet pipe 5 to the tank. To make the valve seat removable, the seat plug 20 is provided with a squared opening 20' by means of which the plug 20 may be screwed in or out.

The casing or body 5' has a nipple 21 55 leading from the valve, and this is provided with an outlet opening 21' on its under side, which opens into the tank. A siphon tube 22 extends from the nipple 21 and is bent over at the top into the overflow pipe 70 23, for "refilling" the closet bowl after the flushing operation. A bracket 24 is attached to the pipe 23 by the clamp 25, and has an arm 26, to which is secured, by the thumb nut 27, a depending rod 28 which extends 75 into a hollow valve stem 29. The upper end of this stem has a collar 30, and a wire loop 31 extends around the hollow stem 29 below said collar and has an end projecting upwardly and hooked into a hole in the end 80 of the trip lever 32, as clearly seen in dotted lines in Fig. 1. This lever is fulcrumed at 33 on the brackets 34 and 35 which are supported on the tank in a suitable way.

The short arm 37 of the trip lever has 85 holes 38 for the passage of pull rods 38 and 39, which are connected at their lower ends to opposite crank arms 40 and 41 projecting from the rock shaft 42 which is mounted in brackets 43 secured to the underside of the 90 flush tank or in any other suitable position.

The rock shaft is operated by a handle 45 on the arm 41. The rock shaft also has opposite lugs 40' and 41' which extend at different angles with respect to the shaft 95 45 and which are adapted to control or limit the throw of the rock shaft in either direction by contact with the bottom of the tank or other fixed part.

The hollow stem 29 is provided with an 100 external tapered or conical part 46, at the top of which is a collar 47. Adjustably mounted on the float rod 11 is an arm 48, secured to the rod by a clamp 47', and provided at its outer end with a cam lug 50. 105 Another arm 51 is fastened to the rod by the clamp 52 and this arm 51 carries a swinging member 51' pivoted thereto at 51'', and a cam lug 53 is secured to the side of this member in position to engage the stirrup 56 110 under certain conditions. The member 51' is normally pressed to parallel position with

respect to the arm 51 by a spring 51' which is fastened to the head 51' at the outer end of the arm and bears at its end 53' against the lower part of the swinging member. 5 The purpose of this yielding construction is to allow the lug 53 to "snap" back sufficiently to pass the stirrup without breakage if the trip lever should be operated while the water is refilling the tank. If the lug 10 53 were rigid with the arm and should strike the stirrup while the float is rising it might break the parts, but the yielding construction permits it to slip by. Secured between the bracket 26 and the thumb nut 15 27 is a horizontal plate 54 to the outer end of which is hinged a downwardly extending catch plate 55 provided with a stirrup portion 56. A spring 57 tends to spring the plate 55 inwardly so that the stirrup 56 contacts with the hollow stem 29 or the conical part 46 on said stem, as the case may be. A bulb 59 is secured on the lower end of the hollow stem 29 and closes against the seat 60, controlling the outlet through the flush 20 pipe 61 which is connected to the closet in the usual way. Different stages of water are indicated in the tank by the lines A 25 and B.

In operation, it is assumed that when full, 30 the water in the tank will stand at the level A, the inlet valve being then forced to closed position by the float, and if it is desired to use the whole amount of water contained in the tank at a single operation, the handle 45 35 is thrown to the right, as shown in dotted lines in Fig. 1. This action will cause the trip lever 32 to move to the dotted line position in Fig. 1, the end 37 being pulled down by the rod 38, and the valve 59 being lifted 40 by the connection 31 to the valve stem 29, and the water flows out through the flushing pipe. As the water lowers the rod 11 and float 12 drop as shown in dotted lines, and in this position the lug 53 on the arm 45 45 will engage with and rest on the stirrup or catch 56, as shown in dotted lines, said stirrup or catch being located in the line of movement of said lug, and thereby the drop or downward movement of the float and arm 50 are stopped and the valve 59 is released and will close in the usual manner, and the inlet 55 valve being open, the tank will refill, and the float and connected parts will resume their normal positions, as shown in full lines in Fig. 1. Assuming that it is desired to use only a portion of the water in the tank at a single operation, (as shown between the water lines A and B), the handle 45 is 60 swung to the left as shown in dotted lines in Fig. 5, and the trip lever 32 will lift only slightly as shown in dotted lines in Fig. 5. It will be understood that the different angles of the stop lugs 40' and 41' control the extent of the different movements. As

the float then falls and arm 51 describes an 65 arc in its downward movement, its lug 53 will engage in the catch or stirrup 56 of the plate 55 and will rest therein, thereby preventing further drop of the float. Meanwhile the valve 59 will be released and will 70 close and the tank will refill through the inlet valve.

It is to be understood that when the valve stem 29 is lifted to its full extent, as when the handle 45 is swung to the right, the 75 cone 46 will pass the lower end of the swinging plate 55 which will then swing in against the stem 29 as shown in Fig. 2, in such position that the lug 53 on the arm 51 will pass over and not engage in the stirrup 80 56, but the lug 50 will, and the lower end of the plate 55 engaging under the cone 46 will hold the outlet valve in raised position until the lug 50 on the arm 48 strikes the stirrup 85 56 and disengages the plate from the cone, thereby permitting the valve 59 to drop and close. But when the handle 45 is turned to the left, and the valve 59 is lifted only a slight distance, the lower end of the plate 55 will catch under the collar 47, as shown 90 in Fig. 6, in which position the stirrup 56 will be in the line of movement of the lug 53 and will be engaged thereby and swung out to release the valve stem and allow it to close, with the water at the level B. 95

What I claim as new is:

1. In a flushing apparatus, the combination of a tank provided with inlet and outlet valves, the latter having a stem with a plurality of projections thereon at different 100 heights, a float and its lever operatively connected to the inlet valve, a trip-lever connected to the outlet valve and adapted to be moved to different positions to lift said valve more or less, a catch engageable with one of 105 said projections according to the extent said valve is lifted, and a plurality of projections on the float lever adapted to selectively strike and release said catch according to the height the outlet valve is lifted. 110

2. In a flushing apparatus, the combination of a tank provided with inlet and outlet valves, a trip lever operatively connected to the outlet valve and movable to different positions to lift said valve more or less, a float 115 operatively connected to the inlet valve, means to hold the outlet valve in open position, and means controlled by the float to release said holding means at different positions of the float, according to the extent 120 to which said valve was lifted.

3. In a flushing apparatus, the combination of a tank provided with inlet and outlet valves, a float in the tank controlling the inlet valve, the outlet valve having a stem provided with upper and lower projections, a catch engageable with either of said projections, to hold the valve in open position, 125

a trip lever operatively connected to said stem and movable to selectively lift the valve to permit the catch to engage one or other of said projections, and means carried by the float to selectively release said catch from the projection with which it is engaged.

4. In a flushing apparatus, the combination of a flushing tank having inlet and outlet valves, a trip lever operatively connected with the outlet valve, an operating lever which may be turned in either direction, a plurality of connecting members between the operating lever and the trip lever to respectively operate the latter when the former is turned either way, stops for the operating lever located in different positions with respect thereto and adapted to permit a different extent of movement of the lever when turned in opposite directions, whereby the outlet valve is opened more or less, a float controlling the inlet valve, a catch engageable with the outlet valve and adapted to hold the same open in either position, and

means actuated by the float to release the catch in either position of the valve.

5. In a flushing apparatus, the combination of a tank provided with inlet and outlet valves, the outlet valve having a stem with an incline thereon, means to lift the outlet valve to different positions, a yielding catch adapted to hold the outlet valve in open position, and engageable with the incline to locate the catch in different positions according to the extent the outer valve is lifted, a float controlling the inlet valve, and a plurality of arms carried by the float and projecting in different positions to selectively engage and release the catch as the float falls, to permit the outlet valve to close at different stages of the water level in the tank.

In testimony whereof, I do affix my signature in presence of two witnesses.

GEORGE SCHONMEYER.
